UNITED STATES PATENT OFFICE.

WILLIAM JOHN DEMMING, OF CLEVELAND, OHIO, ASSIGNOR TO THE AMERICAN MULTIGRAPH COMPANY, OF CLEVELAND, OHIO, A CORPORATION OF OHIO.

MECHANISM FOR ASSEMBLING PRINTING STRIPS.

Application filed August 21, 1922. Serial No. 583,192.

To all whom it may concern:

Be it known that I, WILLIAM JOHN DEMMING, a citizen of the United States, residing at Cleveland, in the county of Cuyahoga and State of Ohio, have invented a certain new and useful Improvement in Mechanism for Assembling Printing Strips, of which the following is a full, clear, and exact description, reference being had to the accompanying drawings.

This invention relates to mechanism for assembling short ribbons or strips of metal, on which type characters have been formed, onto a holder or carrier which may be used in a suitable printing mechanism to print the matter thus composed.

More particularly the invention is concerned with assembling the embossed type carrying strips, such, for example, as may be formed by a mechanism shown, described and claimed in the prior application of Clifton Chisholm, Serial No. 535,311, filed February 9, 1922, by moving these strips longitudinally into engagement with rows of lugs or bosses or similar engaging devices, such as are formed upon address plates of well-known type. As an example of such a plate or holder I call attention to that shown, described and claimed in my Patent No. 1,438,584, issued December 12th, 1922.

My copending application No. 674,649 filed November 14th, 1923, shows a mechanism for automatically delivering embossed strips from the machine in which they are made onto a suitable form, shown as a flexible blanket mounted in cylindrical shape and periodically turned about its axis. The claims originating in the present application covering also the structure in such latter copending application have been transferred to that application, and reference is accordingly made to it for broad claims covering the present structure. The invention claimed in this application on the other hand is concerned with the assemblage of embossed strips on an address plate or other flat form, with a hand feeding of the strips onto the form, with backward movement of the strips on the form to bring them in various offset positions, and with other features not specifically disclosed in that copending application.

The present invention includes means for successively feeding embossed strips as they

are delivered from the machine and suitably positioning them in successive rows upon an address plate or other flat form, and the essential objects of the invention are to provide a simple, effective and easily operable mechanism for taking these severed embossed strips from an embossing machine and positioning them upon a holder for subsequent printing.

Other objects include the convenient arrangement of the mechanism whereby the holders filled with the strips, that is upon which the strips have been positioned, may be readily removed and replaced.

More specific objects include so constructing the device that the advancement line for line, of the holder receiving the strips may follow automatically consequent upon the operation of the mechanism which feeds the strip on to the holder and the strips may be slid thereon without any defacement or distortion. A further specific object is the provision of a convenient and readily operable means for sliding the strips longitudinally upon the securing means on the holder to position them in the alignment desired. For example, when assembling these strips onto address plates the various strips may be of different lengths, and the positioning may be in different vertical alignment for each line, or if assembling upon a larger holder the positioning of the lines may provide for paragraphing, inset spacing etc. The above and other objects will become more apparent from the following description which relates to the drawings illustrating a preferred embodiment of my assembling mechanism. The essential characteristics of the present invention are summarized in the appended claims.

In the drawings Fig. 1 is a side elevation of my mechanism shown as mounted at the side of a strip embossing machine, only a portion of the frame of which is illustrated in this view; Fig. 2 is a plan of the same; Fig. 3 is an enlarged elevation of an address plate shown as receiving the embossed strips; Fig. 4 is an end elevation of the mechanism shown in Figs. 1 and 2 looking toward the device from the right hand end as shown in Fig. 1; Fig. 5 is a horizontal sectional detail of the feed rolls for progressing the strip and the channel guideway and means for moving the strip along the

guideway; Fig. 6 is a plan view of the parts shown in Fig. 5, the rolls, however, being shown in section; Fig. 7 is a perspective detail of the parts forming the guideway and 5 one of the elements for moving the strip from the rolls toward the receiving holder; Fig. 8 is an end elevation of the parts shown in Fig. 7; Fig. 9 is a section through these parts taken substantially on a plane indicated by the line 9—9 of Fig. 6; Fig. 10 is a similar section on a plane indicated by the line 10—10 of Fig. 6; Fig. 11 is a section elevation showing one of the rolls, the 10 guideway, and one of the moving mechanisms for progressing the strip and illustrating the mechanism for advancing the holder line for line to receive the successive strips, the parts in front of this view being omitted for clearness of illustration 15 and the section being taken substantially upon the line 11—11 of Fig. 12; Fig. 12 is a transverse section showing the holder and the mechanism for positioning the lines on the holder, the plane of the section being taken substantially on the line 12—12 of 20 Fig. 2; Fig. 13 is a vertical section through the plate carrier and advancing mechanism, the plane of the section being indicated by the line 13—13 of Fig. 11; Fig. 14 is a horizontal sectional detail on the same scale as Fig. 12 showing the mechanism for operating the line positioning means; Figs. 15, 25 16 and 17 are diagrammatic sectional details showing different positions of the means for positioning the line on the holder; Fig. 18 is a sectional detail illustrating the means for securing and the manner of releasing the address plate or like holder.

It will be seen from the drawings that 30 my assembling mechanism is coupled to the delivery end of a suitable embossing machine having a pair of feeding rollers 1 and 2 progressing the embossed address strip designated S into a channel or guideway 5, from which it is delivered by my mechanism to a strip carrier such as an address plate P mounted upon a carrier 10, the plate being progressed along the channel and then slid longitudinally of the holder P in either 35 direction by a positioning device 20, operated through a system of levers and gearing by a hand lever 25, all of these being carried by a suitable frame and brackets which may be directly attached to the frame of an embossing machine, a portion of which is indicated at 30 in Figs. 1 and 2. These frame and bracket members consist of a bracket 3 forming bearings for the shafts of the rollers 1 and 2, and carrying extensions on 40 which the strip guide members forming the guide 5 are mounted; a horizontal main frame member 15 forming a guideway and slide for the strip progressing elements; an upright bracket 12 forming a guideway 45 and mounting the mechanism for support-

ing and moving the carrier 10 for the strip holder; and an auxiliary bracket 22 on which the hand operated lever 25 and its gearing are mounted.

The rolls 1 and 2 are shown as mounted on 50 parallel vertical shafts 4 geared together by intermeshing spur gears 6, one of the shafts being driven by suitable mechanism acting through the bevel gear indicated at 7 shown at the lower end of one of the shafts 75 4. These rollers 1 and 2 carry pairs of opposed flanges, one pair adapted to fit the rounded edges of the embossed strip and the other pair adapted to engage the inwardly turned flanges of the strip, tightly 80 embracing the same with rolling contact, thereby progressing the strip from left to right, to move it from the position as shown in Fig. 6 onto the guide 5. This guide may comprise a bar 8 secured at its forward end 85 in the bracket member 11 and extending toward the holder carrier 10, and shown as being provided with small ribs 13, each formed with an overhang to receive the flanges of the embossed strips S. This bar 90 is slotted between the ribs 13 near one end and into this slot extends a slide 14 guided by the ribs and having a tongue extending between the rolls and provided with a hooked end 16. This hook normally stands 95 between the ribs of the rolls until the strip S is delivered from the rolls, bringing the shoulder of this hook opposite the end of the strip, whereby a longitudinal movement of the slide 14 may progress the embossed strip along the guide rails 13. The hooked end 16 of the slide 14 is yielding to allow ready passage of the strip and to cause the shoulder of the hook to spring across the end of the strip. Contiguous with the bar 100 105 8 is shown a stiffening member 18 terminating in a head 19, fitted closely into the opening in the bracket 11 the entire guide member being held as by a screw 21. Integral with this head is a curved tongue 22 adapted 110 to lie complementary to the roll 1, between the flanges to assure accurately guiding the strip onto the ribs 13, the one face of this tongue merging with a flat guiding surface 115 23 a distance past the inner ends of the rails 13 to thus accurately guide the flanges of the strip S into engagement with these rails. 120 The slide 14 carrying the hook 16 is shown as actuated by a lever 26 pivotally connected by a screw 27 with the slide 14, and attached by a pivoted link 28 to the bracket 11 to allow swinging movement of the lever, while its lower end projects downwardly into the path of the projection 29 (Figs. 1 and 11) on a sliding bar 32 carried by the 125 guideway formed on the frame member 15. The opposite side of the lower end of the lever 26 is engaged by a projection 33 for swinging this lever in the opposite direction. This projection is rigid with the strip 130

moving slide to be presently described. The slide 32 is shown secured to the guide frame 15 by a screw 34 extending through an elongated opening 35 embracing the shank of the screw. The opposite end of this slide 32 is rigid with an enlarged head 36 fitting into a guiding surface on the frame 15. Additional guiding means for this slide may be provided by a rod 38 rigid with the head 10 and slidably extending through an ear on an arm 39 extending from the bracket 12. A spring 37 shown as attached at one end to the slide 32 and at the other end to the upright frame bracket 12, moves this slide 32 15 in one direction, whereby the lever 26 moves the slide 14 in one direction thrusting the hooked end 16 between the rolls. The return movement is caused by the hand lever 25 through the projection 33, as will be hereinafter described.

As the strip is brought to the position shown in Fig. 11 it is engaged by one end of the hook member 20 and its longitudinal movement is completed to shove the strip 25 from the guide rails 13 onto a row of overhanging projections P^1 on the address plate P , whereupon this address plate is moved upwardly to receive the next embossed line strip upon the next row of projections. 30 This upward movement is caused by moving the carrier 10 upwardly through a slide strip 40, mounted in a guideway on the bracket 12, and having a series of downwardly facing teeth 41 engaged by a dog 42 pivoted at 43 to the slide 32. This dog is normally urged to the left by a plunger 44 which may be actuated by a spring 45 mounted in a guiding cavity in the head 36 of the slide whereby in one position of the slide 32 this dog is thrust to the left, stopping against a pin 46 as shown in Fig. 1. The subsequent movement of the slide to the left causes the dog to engage one of the teeth 41, and as it is brought to its upright position, thrust the slide 40 and attached carriage 10 upwardly the distance of the space of one line on the carrier or plate P . Each successive position of the carrier and plate is retained by a latch dog 47 shown as pivoted at 48 to the bracket 12, and having a nose 49 engaging the teeth 50 on the slide 40, under the influence of a spring 51. Pivoted at the rear of the slide 40 is an upwardly extending handle 52 which may be grasped by hand to raise the slide and carrier 10 and incidentally the plate, or which may be swung about its pivot 53 to engage a roller 54 carried by the dog 47 to hold the nose 49 of the dog 47 out of engagement with the teeth 40 to permit the downward movement of the slide and carrier to bring a plate or holder carried thereby to its initial position. This downward movement is accomplished when the dog 42 is in the position shown in Fig. 1.

The action of the swinging hook 20 to move the strip S in either direction and the arrangement for accomplishing this will now be described. This hook member 20 is shown as mounted upon a vertical shaft 56 70 and secured to a collar 57 rigid with the upper end of the shaft while fitting a flat surface on the upper end of a boss 58, formed upon a main slide 60. This slide 60 transports this hook 20 and actuates the slide 14. 75

On the lower end of the shaft 56 may be rigidly secured a rocking crank member 65 having a crank pin 66 engaging a recess 68 in a slide 70 movable longitudinally of the frame 15 in guides 71 formed in the frame 80 (Figs. 12 and 14). Attached to the lower side of this slide 70 beneath these guideways by a pivot screw, indicated at 74, is a link 75 (Figs. 1 and 14) in turn pivoted at the other end, through the pivot pin 76, to a lever 80 journaled on a pin 81 carried by a suitable boss at the outer end of the bracket 22. Rigid with the upper side of an enlargement of the lever 80 embracing the pivot pin and forming a bearing therefor is shown a gear 84 surrounded by a suitable cover 85. This gear 84 may be rotated to swing the lever 80 by a gear 86 actuated by a stub shaft 87 on which the hand lever 25 is mounted. 95

The opposite end of the crank member 65 is shown as bifurcated to straddle a movable stop 90 carried on the lower end of a rotatable pin 91 extending through the bracket member 60 and provided at its upper end with a collar and thumb pin indicated at 94, Fig. 12. This stop 90 and the shaft 56 connect the crank member 65 with the slide 70 through the pin 66, but it will be seen that as the slide 70 starts in one direction it will first rock this crank 65 until the bifurcated portion engages one side of the stop 90, whereupon the slide 60 will follow the movement of the slide 70, but this rocking movement first swings the hook member 20 to move one end inwardly and the other outwardly. The stop portion 90 is eccentric of the pin 91 so that when swung by the thumb pin 94 it may change the relative position of the hook 20 to determine which end shall be in engagement with the strip S , but in either position it permits a rocking of this hook so that the active end may move along the strip without contacting therewith and then move inwardly and engage the strip. 100 105 110 115 120

The slide 60 is shown as guided on one side upon a slide rail 95 secured to an upturned flange of the bracket 15 and fitting into a suitable rabbet in the side of the slide 60, while the other side of the slide embraces a guide rod 96 rigidly carried by the frame member 15. Friction plungers 97 in the slide 60, Figs. 12 and 14, are shown as urged into contact with the rail 95 by springs 98, 125

and tend to prevent inadvertent movement of the slide.

To position the plate on the carrier 10 the side flanges P^2 of the plate are utilized to engage the edges of the carrier 10, while the lower edge of the plate P fits into hooks 100 and at the two upper corners of the plate P may additionally secure it by inwardly turned clips 102 (Fig. 3) through which the plate may be slid downwardly into engagement with the hooks 100. The plate is securely held in this position by pivoted latches 104 in the nature of narrow flat pieces, rocking about a pivot 105 in slots or recesses closely embracing the sides thereof and formed in the carrier 10, while a spring 106 acting on the lower side of each latch tends to swing it upwardly to the position shown in Fig. 18. As the plate is moved downwardly from the position shown in Fig. 18 into engagement with the hooks 100, the subsequent downward movement of the carriage 10 acting against a positioning block 110 carried by the bracket 12 tips these latches forwardly, causing an overhanging edge 107 of each latch to engage the upper side of the plate P . To remove the plate it may simply be grasped and pulled upwardly, the first movement raising the carrier until it reaches its uppermost position whereupon the latches 104 spring rearwardly and the continued upward movement of the plate detaches it from its holding means on the carrier 10.

To summarize the operation of the device we may assume, first, that an embossed strip has been progressed by the rolls 1 and 2 onto the rails 13 and freed from the rolls. The hand lever 25 is then rotated in a direction to swing the lever 80 to the left (Figs. 1 and 2) the first part of this movement swings the rocking crank 65 through the pin 66 until it engages the stop 90, which swings the left hand end of the hook member 20 out of engagement with the strip S but without bringing the opposite end near enough to engage the strip. A continued movement of the lever 80 therefore moves the slide 70 and consequently the slide 60 and hook member 20 along the guideways to the left, and the projection 33 on the slide 70 engages the lower end of the lever 26 to move the slide 14 and its hook 16 to the right, thus engaging the strip as shown in Fig. 5 and moving it in the direction of the arrow in that figure. This brings the left hand end of the hook member 20, designated 20^a, to the position shown in Fig. 5 whereupon the direction of turning of the hand lever 25 is reversed, moving the lever 80 in the opposite direction. Before this results in moving the slide 60 it acts through the pin 66 and crank 65 to swing that crank until the other side of the bifurcated portion thereof engages the stop 90, which allows slight return move-

ment of the hook 16 and permits engagement of the hook 20^a with the end of the strip S , after which the continued movement of the hand lever and lever 80 to the right moves the strip S along the rails 13 and brings that strip onto the carrier plate, causing its flanges to engage the projections P^1 in the manner indicated in Fig. 12. The continued movement may position the strip as desired upon the strip holder, represented by the address plate. This operation is repeated until the desired number of embossed strips are placed upon the holder, whereupon the holder is then lifted and removed as described.

To move an embossed strip on the plate P in the opposite direction, the stop 90 is reversed (see Fig. 17 as compared to Figs. 15 and 16) which causes the reciprocation of the member 20 to be through a position with the hook 20^a outwardly and the hook 20^b standing inwardly. It will be seen from an inspection of these figures that with the parts in the position shown in Fig. 15 the carrier and member 20 may be moving freely to the left where they may engage a strip S and move the same to the right as indicated in Fig. 16. With the parts reversed it will be noted that the hook 20^b is inwardly. This figure shows the parts passing to the right. As soon as the end 20^b passes the end of the strip S the reverse of the movement will throw the end 20^b inwardly, and a continuation of this reverse movement will then progress the strip S to the left. This mechanism is very effective in positioning these strips upon carriers of the general type illustrated.

I claim:

1. A machine for delivering printing strips, a guideway leading therefrom, a flat printing form and means supporting said form adjacent the guideway, means on the form for receiving the strips, means for aligning the last named means with the guideway, and means for periodically feeding the form in its own plane to enable it to receive new lines.

2. The combination with a machine adapted to deliver printing strips having inwardly turned flanges, of a printing form having projections for receiving said flanges to mount the strip thereon, a guideway and means for mounting the printing form with its holding means in alignment with said guideway, a hand lever, and a mechanism operated thereby for moving a strip onto the form.

3. The combination of means for delivering a printing strip, a guideway receiving the printing strip, an address plate having means thereon for holding the printing strip, means for mounting the address plate to align the last named means with the guideway, and means for moving the printing

strip along said guideway and onto said address plate.

4. The combination with means for delivering embossed printing strips having inwardly turned flanges, of a guideway having flanges coacting therewith, an address plate having a series of rows of aligned projections receiving said flanges of the strip, means for supporting the address plate to align said projections with the flanges of the guideway, means for lifting the address plate step by step and means for progressing the strip along said guideway and onto the address plate.

15 5. The combination with means for delivering printing strips, of a guideway having means coacting with the edges of the strip, a printing form having a series of aligned projections receiving said edges of the strip, means for supporting the form to align said projections with the flanges of the guideway, means for progressing the strip along said guideway and onto the form, and means for sliding the strip in either direction along said projections.

6. Means for delivering a printing strip, a guideway for receiving said strip from the delivering means, a printing form having means coacting with the sides of the strip and arranged for a plurality of lines, means for moving the strips from the guideway and onto said form, means for moving the strips backwardly on the form, and means for advancing the form by step by step movement to present successive lines of strip holding means.

7. Means for delivering a printing strip having printing characters formed thereon, a guideway for supporting said strip, means for moving the strip along the guideway, a vertically reciprocable holder adapted to support a flat address plate having rows of projections with a row in registration with the guideway, means for moving a strip from the guideway onto a row of projections of the address plate, and means for raising the holder to present successive rows of projections in alignment with the guideway.

50 8. The combination of means for delivering a printing strip to a printing form, said printing form having means for holding a series of strips in parallel lines, and means for moving the strips longitudinally on the form to initially position the same and adapted to move the same while on the form.

9. The combination with a means for delivering embossed printing strips having flanges, a form to receive said strips from the delivering means and having projections coacting with the flanges to hold the strips in parallel lines thereon, means for moving the strips in either direction on the form to position the same prior to printing.

65 10. In a device of the character described,

the combination with means for delivering a printing strip, of a form having means for holding a series of said strips in parallel lines, a guideway, a slide on the guideway, a device carried by the slide adapted to engage and move the strips into the form, means for advancing the form a line at a time, including a slide carrying the form, a ratchet and dog mechanism advancing it consequent upon the movement of the slide, and means for resetting the ratchet and dog mechanism.

11. In a device of the character described, the combination with a printing form adapted to receive a series of printing strips, means on the form for holding said strips, a guideway, means for delivering the strips to the guideway, a slide for progressing the strips along the guideway, another slide for moving the strips from the guideway onto the form, connections between said slides to cause one slide to act after the other has finished its movement, a lever for moving the first mentioned slide, a hand lever, and power multiplying gearing for moving the first named lever by the hand lever.

12. In a device of the character described, the combination of means for delivering printing strips, a guideway for receiving the strips, a form onto which said strips may be mounted by longitudinal movement with relation to the form, means for moving the strip along the guideway and onto the form in one direction, said means comprising a hook member, means for moving the strip in the other direction including a projection on the same hooked member, and a slide carrying said hook member.

13. In a device of the character described, the combination of means for delivering printing strips, a form onto which said strips may be mounted from the delivering means by longitudinal movement with relation to the form, means for moving the strip onto the form and for sliding the strip in either direction thereon, said means comprising a rockable member having a strip engaging hook at each end, a slide carrying said hook member, a rock shaft for moving said hook member and means for limiting the movement of each hook, said means being shiftable to determine the activity of either hook.

14. In a device of the character described, the combination of a printing strip delivering mechanism, a guideway, a form having holding means onto which the strips may be thrust longitudinally to position them for printing, means for moving the strips along the guideway and on to the form, including a rocking member having a hook at each end, each hook being adapted to engage one end of the strip, means for moving either hooked end into and out of

engagement while the other end is in idle position, and means for carrying the hooked member and for moving it longitudinally.

15. In a device of the character described, 5 the combination of a printing strip delivering mechanism, a form having holding means onto which the strips may be thrust longitudinally to position them for printing, means for moving the strips along the 10 guideway and on to the form, consisting of a rocking member having a hook at each end, each hook being adapted to engage one end of the strip, means for moving either hooked end into and out of engagement 15 while the other end is in idle position, a slide carrying the hooked member, means for moving said slide, a stop governing the rocking movement of the hook member, and means for moving the stop from one position 20 to another to determine the active end of the hooked member.

16. A combination with means for guiding a printing strip, of a flat form having means for holding thereon a plurality of 25 strips, mechanism for moving the strips from the guiding means on to said form, a ratchet bar adapted to move with the form and having teeth corresponding to the distance between lines on the form, and mechanism for moving the ratchet bar to advance the form step by step.

17. A combination with a horizontal guideway and means for delivering printing strips thereto, of a flat form provided 35 with means for holding a plurality of parallel strips, means for holding said form in a vertical position, adapted to register with the guideway, whereby the strips on the form may be read, means for moving said form upwardly step by step to position it to receive a new strip, and mechanism for moving the strips from the guideway onto the registering form.

18. Means for delivering a printing strip 45 having printing characters formed thereon, a guideway for supporting said strip, and means for moving the strip along the guideway, a flat address plate having a series of projections arranged in parallel rows to 50 correspond to printing lines, said projections being adapted to engage and support the strips, means for supporting said address plate in alignment with the guideway, and means for latching the address plate with successive lines of projections in 55 alignment with the guideway.

19. The combination with means for delivering printing members in the form of strips having inwardly turned flanges, a guideway and means for moving said strips along said guideway, a printing form on which such strips may be removably carried, and means for moving the strips onto the printing form from the guideway.

- 65 20. A machine for delivering printing

strips, a guideway leading therefrom, a printing form and means supporting said form adjacent the guideway, means on the form for receiving strips, and means for aligning the last named means with the 70 guideway.

21. The combination with a machine adapted to deliver printing strips having inwardly turned flanges, a printing form having projections for receiving said flanges to mount the strip thereon, a guideway and means for mounting the printing form with its holding means in alignment with said guideway.

22. The combination of means for delivering a printing strip, a guideway receiving the printing strip, a printing form having means thereon for holding the printing strip, means for mounting the form to align the last named means with the guideway, and means for moving the printing strip along said guideway and onto said form.

23. The combination with means for delivering printing strips having inwardly turned flanges, of a guideway having flanges coacting therewith, a printing form having projections receiving said flanges of the strip, means for supporting the form to align said projections with the flanges of the guideway, and means for progressing the strip along said guideway and onto the form.

24. The combination with means for delivering embossed printing strips having inwardly turned flanges, of a guideway having flanges coacting therewith, a printing form having a series of rows of aligned projections receiving said flanges of the strip, means for supporting the form to align said projections with the flanges of the guideway, and means for progressing the strip along said guideway and onto the form.

25. Means for delivering a printing strip, a guideway for receiving said strip from the delivering means, a printing form having said means coacting with the sides of the strip and arranged for a plurality of lines, means for moving the strips from the guideway and onto said form, and means for advancing the form by step by step movement to present successive lines of strip holding means.

26. Means for delivering a printing strip having printing characters thereon, a guideway for supporting said strip, and means for moving the strip along the guideway, a printing form having a series of projections arranged in parallel rows to correspond to printing lines, said projections being adapted to engage and support the strip, means for supporting said form in alignment with the guideway, and means for latching the form with successive lines of projections in alignment with the guideway.

27. Means for delivering a printing strip

- having printing characters formed thereon, a guideway for supporting said strip and means for moving the strip along the guideway, a printing form having a series of 5 projections arranged in parallel rows to correspond to printing lines, said projections being adapted to engage and support the strips, means for supporting said form in alignment with the guideway, means for 10 moving the strip from the guideway onto the form, and means for moving and lateraling the form to present successive rows of projections in alignment with the guideway.
- 15 28. The combination with means for delivering embossed printing strips including a guideway for the strips, of a form adapted to receive and hold said strips in parallel lines, means for advancing the form by 20 a series of step by step movements to present successive lines on the form into alignment with the delivering means, means for moving the strip from the guideway and along the holding means onto the form, and 25 means connecting said moving means with the step by step means whereby each step movement of the form may follow a return movement of the progressing means.
29. In a device of the character described, 30 the combination with means for delivering printing strips to a holder comprising a printing form, said means including a guideway, means for mounting the printing form in a position to receive the strips from the 35 guideway, and means for removably supporting the form to allow removal of the filled strips and replacement by empty forms.
30. The combination with means for delivering embossed printing strips, of a printing form to receive the strips, means for moving the strips onto the form and for holding them thereon, means for supporting the form in position to receive the strips, 40 means for removably securing the form in this position, means for causing a step by step movement of the form consequent upon actuation of the strip moving means.
31. The combination with means for delivering line printing strips, of a printing form to receive the strips, means for moving the strips onto the form and for holding them thereon, means for supporting the form in position to receive the strips, means 45 for removably securing the form in this position, means causing a step by step movement of the form consequent upon actuation of the strip moving means to present successive line strip holding means, and means for resetting the step by step mechanism after filling a form.
32. In a machine of the character described, the combination with opposed continuously rotated rolls adapted to deliver a 50 printing strip, a guideway adapted to receive the strip from the rolls, a printing form, and means for moving the strips from the guideway onto said form.
33. The combination with means for delivering printing strips, a guideway receiving the strips therefrom, a portion of the guideway having a hooked slide member extending between the rolls, and adapted to engage the strips, means for moving said slide member to progress successive strips away from the rolls and along said guideway, a printing form having strip carrying means aligned with said guideway, means engaging and moving the strip from the guideway onto the form, a slide carrying the last mentioned means, and connections between said slide and the first mentioned slide, whereby movement of the last named slide causes movement of the first named slide and hook. 55
34. The combination with continuously operating means for delivering printing strips, a guideway receiving the strips therefrom, a portion of the guideway having a slide member provided with a strip engaging projection extending between the rolls, means for moving said slide member to progress the strip away from the rolls and along said guideway, a printing form having strip carrying means aligned with said guideway, means engaging and moving the strip from the guideway onto the form, and a slide carrying the last mentioned means. 60
35. The combination with continuously driven rolls adapted to receive and deliver a printing strip, a guideway receiving the strip from the rolls, a printing form having strip holding means aligned with the guideway, and mechanism for receiving the strip after delivery from the rolls and adapted to position the same on the guideway. 65
36. In a device of the character described, the combination with a printing form adapted to receive a series of printing strips, means on the form for holding said strips, a guideway, and means for delivering the strips to the guideway, a slide for progressing the strips along the guideway, another slide for moving the strips from the guideway onto the form, each of said slides having a hook for engaging the end of the strip, and operative connections between the slides whereby one hook sets after the other has finished its movement. 70
37. In a device of the character described, the combination with a printing form adapted to receive a series of printing strips, means on the form for holding said strips, a guideway and means for delivering the strips to the guideway, a slide for progressing the strips along the guideway, another slide for moving the strips from the guideway onto the form, each of said slides having a hook for engaging the end of a strip, and mechanism for moving said slides. 75

38. In a delivery mechanism, the combination with means for guiding a printing strip, of a reciprocating carriage, a hook thereon to engage the strip, a shaft carrying the hook, a rocking plate controlling the shaft, means tending to move the plate, and means tending to retard the carriage whereby the hook is swung before the carriage is moved.
- 10 39. In a delivery mechanism, the combination with means for supporting a form, of a reciprocable carriage, a rocking hook thereon adapted to engage a printing strip, a plate connected with the hook and adapted to rock it into such engagement, a reciprocating slide, and a pin and slot connection

between it and the plate, whereby the slide may rock the plate and then reciprocate the carriage.

40. A guideway adapted to slidably support embossed printing strips having flanged edges which converge, a printing form having strip carrying projections over which the strips may extend with their flanges behind the projections, means for supporting the printing form to bring said strip carrying projections into alignment with said guideway, and means for moving the strips from the guideway onto the form.

In testimony whereof, I hereunto affix my signature.

WILLIAM JOHN DEMMING.
